UNITED STATES PATENT OFFICE

154,881

DESIGN FOR A ROOF VENT OR SIMILAR ARTICLE

Sol Ronald Rubin, Los Angeles, Calif.

Application September 18, 1947, Serial No. 141,467

Term of patent 14 years

(Cl. D62—3)

To all whom it may concern:

Be it known that I, Sol Ronald Rubin, a citizen of the United States, residing in Los Angeles, in the county of Los Angeles, State of California, have invented a new, original, and ornamental Design for a Roof Vent or Similar Article, of which the following is a specification, reference being had to the accompanying drawing, forming a part thereof.

Figure 1 is a side view of a roof vent embodying my new design.

Figure 2 is a top view thereof.

Figure 3 is a top perspective view on an enlarged scale; and

Figure 4 is a bottom perspective view thereof.

The characteristic feature of the design for roof vent disclosed resides in the outer shield having the specific configuration shown.

I claim:

The ornamental design for a roof vent or similar article, as shown and described.

SOL RONALD RUBIN.
